US0D1110385S

(12) **United States Design Patent** (10) **Patent No.:** **US D1,110,385 S**
(45) **Date of Patent:** **** Jan. 27, 2026**

(54) **IMAGING DEVICE**

(71) Applicant: **Target Brands, Inc.**, Minneapolis, MN (US)

(72) Inventors: **Anup Jayapal Rao**, Bengaluru (IN); **Shanavas M S**, Bengaluru (IN); **Wasim Salih Thari**, Bengaluru (IN)

(73) Assignee: **Target Brands, Inc.**, Minneapolis, MN (US)

(**) Term: **15 Years**

(21) Appl. No.: **29/828,424**

(22) Filed: **Feb. 25, 2022**

(51) LOC (15) Cl. **16-01**

(52) U.S. Cl.

USPC **D16/203**

(58) **Field of Classification Search**

USPC ..... D16/200-203, 208, 211, 213-214, D16/217-218; D10/46, 49, 104.1, 106, 1, D10/106.6; D14/125, 129, 138 C, 209.1, D14/214-215; D21/513-517

(57) **CLAIM**

The ornamental design for an imaging device as shown and described.

DESCRIPTION

FIG. 1 is top, front perspective view of an imaging device; FIG. 2 is a front elevational view of the imaging device of FIG. 1;

FIG. 3 is a rear elevational view of the imaging device of FIG. 1;

FIG. 4 is a first side elevational view of the imaging device of FIG. 1;

FIG. 5 is a second side elevational view of the imaging device of FIG. 1;

FIG. 6 is a top plan view of the imaging device of FIG. 1; FIG. 7 is a bottom plan view of the imaging device of FIG. 1; and,

FIG. 8 is a bottom, rear perspective view of the imaging device of FIG. 1.

In the drawings, the dash-dot-dash broken lines indicate the boundaries of the claim; the evenly spaced broken lines depict portions of the imaging device and form no part of the claimed design.

1 Claim, 6 Drawing Sheets
